UNITED STATES PATENT OFFICE

EDWARD INGRAHAM, OF BRISTOL, CONNECTICUT, ASSIGNOR TO THE E. INGRAHAM COMPANY, OF BRISTOL, CONNECTICUT, A CORPORATION

DESIGN FOR A CLOCK DIAL

Application filed January 2, 1931. Serial No. 38,186. Term of patent 7 years.

To all whom it may concern:

Be it known that I, **EDWARD INGRAHAM**, a citizen of the United States, residing at Bristol, in the county of Hartford and State of Connecticut, have invented a new, original, and ornamental Design for a Clock-Dial, of which the following is a specification, reference being had to the accompanying drawing, forming part thereof.

The figure is a face view of a clock-dial showing my new design. The rectangular dotted outline shown as surrounding my im-

proved design represents merely the paper or other material upon which the same is impressed, the salient feature of my design being the location upon the dial of a substantially-solid sector or half-moon enclosed within a concentric band of numerals differentiated in color from the body of the dial.

I claim:

The ornamental design for a clock-dial as shown and described.

EDWARD INGRAHAM.
